Patented May 24, 1921.

2 SHEETS—SHEET 1.

UNITED STATES PATENT OFFICE.

GEORGE A. YANOCHOWSKI, OF CHICAGO, ILLINOIS, AND HARRY E. HERSHY, OF WHITEWATER, KANSAS, ASSIGNORS TO AUTOMATIC ELECTRIC COMPANY, OF CHICAGO, ILLINOIS, A CORPORATION OF ILLINOIS.

SEMI-AUTOMATIC TELEPHONE SYSTEM.

1,379,017.

Specification of Letters Patent.

Patented May 24, 1921.

Application filed February 21, 1916. Serial No. 79,662.

To all whom it may concern:

Be it known that we, GEORGE A. YANOCHOWSKI and HARRY E. HERSHY, both citizens of the United States of America, and 5 residents, respectively, of Chicago, county of Cook, and State of Illinois, and Whitewater, county of Butler, and State of Kansas, have invented certain new and useful 10 Improvements in Semi-Automatic Telephone Systems, of which the following is a specification.

Our invention relates to semi-automatic telephone systems in general, but has particular reference to the means for indicating to an operator in such a system that a called line is busy. More specifically, our 15 invention relates to the provision of supervisory signals associated with operators' cord circuits and to the method of controlling said signals when connection is attempted with a busy line.

Heretofore various means have been employed for controlling such a signal, but to the best of our present knowledge, all previous 25 systems employ special means associated with the connector switches for controlling the signal in the operator's cord circuit. Or, at any rate, the connector switch used in the unsuccessful call is instrumental in some way in effecting the continued actuation of the signal, and is, therefore, tied up and cannot be used for other connections until released by some act of an operator.

In our improved system we employ a connector switch which releases when an attempt is made to connect with a busy line and which, before so doing, initiates an operation at the operator's cord circuit where- 35 by the busy flash signal is controlled, and a busy tone is transmitted to the calling subscriber.

The principal object of our invention is the provision of means whereby the foregoing is accomplished independently of the automatic switches, except for the initial operation above mentioned, and whereby, after their release, the automatic switches are made accessible for use in other connec- 45 tions.

Further objects relate to the provision of certain details of circuit improvement tending to increase the general efficiency and

serviceability of a telephone exchange system of this character.

To accomplish the foregoing and other useful ends our invention comprises means which will be hereinafter fully explained, reference being had to the accompanying drawings, in which Figures 1 and 2, taken 5 in order with the lines at the ends thereof in alinement, represent a complete circuit connection between a calling substation A and a called substation A' in a system embodying the principles of our invention. 60 The said connection has been established through the medium of the individual line switch C, answering jack J, cord circuit F, multiple jack J', line switch C', and connector H.

Referring now to Fig. 1, the substation A may be of any suitable or approved type, and, as herein represented, comprises the usual receiver 9, transmitter 10, ringer 11, and condenser 12.

The substation A' (Fig. 2) is similar to the substation A.

The subscriber's individual switch C (Fig. 1) is of the general type of subscriber's switch shown in British patent to 80 R. W. James No. 26,301 of 1906; being, however, of the particular type disclosed in British patent to T. G. Martin, No. 1419 of 1910. This line switch comprises among other details, a plunger (not shown) attached to the end of a so-called plunger arm 13 which is controlled by the magnet 14. The magnet 14, comprises four windings, namely, a pull down winding 15, cut-off or holding winding 16, line winding 17 and an auxiliary winding 18. The core of the magnet 14 is so constructed that the magnetic circuit of the windings 15 and 16 is separate from that of the windings 17 and 18. This magnet also controls the cut-off armature 19.

The pull-in winding 15 operates both the plunger arm 13 and the armature 19, while the cut-off or holding winding 16 is strong enough only to operate the cut-off armature 19 and to hold the plunger arm 100 13 in its operated position. When the plunger arm 13 is operated, the plunger is forced into a bank of contact springs, forcing the springs 20, 21, 22, and 23 into engagement with the springs 24, 25, 26, and 27, respectively. Although only one set of springs

(20 to 27) is shown, each line switch is provided with a plurality of such sets, each set forming the terminal of a trunk line leading to an answering jack. Each trunk line 5 is connected in multiple with the corresponding springs of all the line switches of the group which is controlled by the master switch D. The switch C is controlled by the subscriber through the medium of the line 10 winding 17, as will hereinafter be more fully explained.

The line switches C' and C² are of the same type as the switch C.

The master switch D (Fig. 1) is of the same general type as that disclosed in British patent to R. W. James No. 26,301 of 1906; being, however, of the particular type disclosed in British patent to T. G. Martin No. 1419 of 1910. The function of the master switch, as is well known, is to maintain the plungers of all the idle line switches in position to engage the terminals of an idle trunk line.

The answering jack equipment E consists 25 of the usual line relay 28, cut-off relay 29, line lamp 30 and answering jack J.

The cord circuit F is of a well known type and comprises the usual answering and calling plugs P and P', inductively connected 30 through the medium of the condensers 31 and 32. The lamps 33 and 34 are the usual supervisory lamps. The relay 35 is a polarized relay. The key K is a listening key for connecting the operator's talking set (not 35 shown) with the cord circuit. The key K' is a calling device key, the purpose of which is to connect the calling device 78 with the cord circuit, through the medium of which the operator may control the automatic 40 switches to set up the proper connection. This calling device may be of any desired type, such, for instance, as that shown in British patent to S. G. S. Dicker No. 29,654 of 1910. By suitable manipulations of the 45 dial the operator may interrupt the bridge across the trunk line a number of times corresponding to each of the digits of the number of the called subscriber.

The connector switch H (Fig. 2) is of the same general type of connector switch as 50 disclosed in United States Letters Patent No. 815,176 granted March 13, 1906, to Keith, Erickson and Erickson; the circuits, however, being modified to adapt the switch 55 to operate in a system in which the central office apparatus is controlled by impulses delivered over the two sides of the line in series. Among other details the connector H comprises a bank of contacts arranged in 60 horizontal rows or levels, which contacts are adapted to be engaged by a set of wipers 36, 37, and 38 carried upon a shaft (not shown) which has a vertical movement controlled by the vertical magnet 39 and a rotary movement controlled by the rotary magnet 40.

The usual side switch comprising the wipers 41, 42, 43, and 44 is controlled by the private magnet 45 in the usual and well known manner. The operations of various parts of the switch are controlled through the medium of 70 the double-wound relay 46, said relay being connected with the line through the reversing springs of a so-called back bridge relay 47, through the windings of which latter relay the called line is provided with talking 75 current. The ringer relay 48 affords means by which ringing current is applied to the called line. Means for permitting the switch to be restored to normal position are provided in the release magnet 49, which, upon 80 energizing, withdraws the retaining double-dog from the shaft, thereby permitting the shaft and wipers to be restored to their normal position. The springs 50 and 51 close only when the switch shaft has been raised 85 one or more steps from its lowest position. The relays 52 and 53 are slow acting, that is, slow to release their armatures upon de-energizing.

For the purpose of supplying battery current 90 for operating the apparatus and for talking purposes, there is shown the battery B having one terminal grounded at G. For the purpose of supplying ringing current there is shown the ringing current 95 generator R. The busy signaling machine Q, as represented herein, comprises an induction coil or transformer, the primary winding of which is included in a local circuit with a battery and an interrupting device. 100 Through the medium of this interrupting device, an interrupted current is supplied to the primary winding, thereby inducing an intermittent alternating current in the secondary winding, whereby, when said winding 105 is connected with the subscriber's line, a buzzing sound is heard in the receiver.

A general description of the apparatus having been given, it will now be explained how a connection is established between a 110 calling substation A and a called substation A'. It will also be explained how, if the called substation is busy, all of the automatic switches controlled by the operator in setting up a connection are automatically 115 released and returned to normal position, while the calling subscriber is receiving the busy signal, which is in this case applied to the calling line at the cord circuit. In addition it will be shown how the called supervisory lamp is caused to flash, thus informing the operator that the number called is busy. It will be assumed that the 120 number of the called substation is 22. Since the apparatus disclosed herein is in general 125 well known in the art, and is described in the publications herein referred to, its operation will be explained in a more or less general manner.

When the subscriber at substation A re- 130

moves the receiver 9 preliminary to making a call, an energizing circuit is closed through the line winding 17, of the line switch C. This circuit extends from ground 5 G^1 through springs 54 and 55, conductor 56, through substation A, conductor 57, springs 58 and 59 and the line winding 17 to battery B. The armature 60, is thereby operated and closes a circuit from ground 10 G^1 through springs 54 and 61, pull-in winding 15, auxiliary winding 18 and the springs 62 to battery B. The pull-in winding 15, upon energizing, attracts both the armature 19 and the plunger arm 13. The plunger 15 arm, upon being attracted, forces the plunger which is attached to the end thereof into the bank of trunk terminals to which it has access, forcing the springs 20, 21, 22, and 23 into engagement with springs 24, 25, 26, 20 and 27, respectively. The engagement of springs 20 and 23 with springs 24 and 27, respectively, closes a circuit through the line relay 28 associated with the answering jack E. This circuit extends from ground 25 G^2 through springs 63 and 64, springs 24 and 20, conductor 57, to and through substation A, conductor 56, bank springs 23 and 27, springs 65 and 66, and the relay 28 to battery B.

30 The energization of relay 28 closes a circuit extending from ground G^3 , through springs 67, bank springs 25 and 21, to the point 68, whence one branch extends over conductor 69 to the connector private bank 35 contact associated with the calling line, and multiples of the same. Another branch extends from the point 68 through the holding winding 16 of line switch C to battery B. This circuit through the holding winding 16 is closed before the armature 60 falls back, after the circuit through the line winding 17 is broken by the attraction of the armature 19. The armature 60 does not fall back immediately upon the pulling 40 up of the armature 19, owing to the effect of the winding 18, which, until the plunger arm 13 is completely attracted, is in series with the winding 15. Upon the complete attraction of the plunger arm the retraction 45 of armature 60 is further retarded by the short circuiting of winding 18 at springs 70, thereby introducing the well known slow action. Thus the armature 60 is held in an operated position until enough time has 50 elapsed for the circuit through the winding 16 to be closed, whereby the plunger arm 13 is held in an operated position.

A further result of the energization of 55 relay 28 is the closure of a circuit through the line lamp 30. This circuit extends from ground G^3 through contacts of springs 67^a, said line lamp 30 to battery B, thus causing the lamp 30 to glow. The operator upon seeing the lamp 30 glowing, raises the plug 60 P from the plug seat switch 71 and inserts

said plug in jack J. When the plug is removed from the plug seat 71, a circuit is closed from the ground G^4 through plug seat switch 71, lamp 33, and the springs 72 to battery B. Upon the insertion of plug P 70 in jack J a circuit is closed extending from ground G^5 through resistance 73, sleeve of plug P, sleeve of jack J, and the cut-off relay 29 to battery B. The cut-off relay 29, upon energizing, cuts off the line relay 28 75 and extends the connection to the cord circuit F, and since the springs 75^a of said relay are adjusted to make contact before springs 67 of relay 28 break from their contacts, the ground G^2 now affords a holding 80 circuit for the winding 16 of line switch C to take the place of ground G^3 which will be removed upon the deenergization of relay 28. The circuit for the new holding ground extends from ground G^2 through 85 contacts of springs 75^a, bank contacts 25 and 21, and hold-in winding 16 to battery B. When the connection is extended to the cord circuit F a circuit is closed extending from ground G^6 through coil 74, tip of plug P, 90 tip spring of jack J, springs 75 and 64, to and through substation A over a circuit previously traced, springs 65 and 76, ring spring of jack J, ring of plug P, and the relay 77 to battery B. The relay 77, upon energizing, 95 opens the circuit of lamp 33 previously referred to. The operator now operates the key K and converses with the calling subscriber. Upon learning the desired number, she operates the key K', thereby separating 100 the answering and calling ends of the cord circuit and bridging the calling device 78 across the calling end, and then inserts the plug P' in an idle outgoing trunk jack J'.

Upon the insertion of the plug P' into the 105 jack J' and due to the fact that the calling device 78 is bridged across the line conductors of the cord circuit an energizing circuit for the line winding of the switch C² is closed. The line winding of the switch C², 110 upon energizing, causes said switch C² to draw in its plunger-arm 95 in the same manner as was described regarding line switch C to thereby extend the connection to the line relay 46 of the connector H. A circuit may now be traced from ground G^7 through lower winding of relay 46, springs 79 and 80, springs 119, bank springs 81 and 82, conductor 83, ring spring of jack J', ring of plug P', springs 84, contact of key K', 120 calling device 78, contact of key K', relay 85, tip of plug P', tip spring of jack J', conductor 86, springs 87 and 88, springs 89 and 90, and the upper winding of relay 46 to battery B. The line relay 46, upon energizing, 125 closes a circuit through the relay 52. This circuit extends from ground G^8 through contacts of springs 99 and 99^a and relay 52 to battery B. The relay 52 in turn, upon energizing, closes a circuit from ground G^8 130

through springs 91, springs 92 and 93, and the holding winding 94 to battery B. The holding winding 94, energizes over this circuit and operates it to hold the plunger arm 5 95 in an operated position. It will have been noticed that the energizing circuit of the line winding of the line switch C² and the later described circuit of the line relay 46, both included the relay 85 in the cord 10 circuit F. The jack J' is so adjusted, that when the plug P' is inserted, the tip and ring of plug and jack make contact before the springs 96 are closed. In this way the relay 85 will be energized and open the circuit of relay 97, at the springs 98, before the circuit of said relay is completed at 15 springs 96.

The operator now operates her calling device for the first digit of the called number, 20 whereby the calling device impulse springs are separated twice momentarily, each time breaking the circuit of the line relay 46 of the connector H. The relay 52 of the connector being slow acting, does not deenergize during the momentary interruptions of 25 its circuit by the relay 46, and consequently each time the latter relay deenergizes, an impulse is transmitted over the circuit extending from ground G⁹ through springs 30 99 and 100, springs 101 and 102, relay 53, vertical magnet 39, and the side switch wiper 41 (in first position) to battery B. The vertical magnet receives two impulses over this circuit and operates to raise the 35 switch shaft and wipers two steps to a position opposite the second row or level of bank contacts, and at the same time the shaft controlled springs 50 and 51 are closed. The slow acting relay 53 is maintained in 40 its energized position continuously while impulses are being transmitted to the vertical magnet through it, and in its energized position, closes a circuit from ground G¹⁰ through springs 103 and 104, and the private magnet 45, to battery B. This circuit is broken when the relay 53 deenergizes after the last impulse has been delivered to the vertical magnet, the breaking of said circuit causing the private magnet 45 to de- 45 energize, thus permitting the side switch to pass to second position. In passing from first to second position, the side switch wiper 41 transfers the battery connection from the vertical magnet 39 to the rotary magnet 40. 50 The operator now operates the calling device for the last digit 2, in response to which the connector line relay operates to transmit two impulses through the rotary magnet 40, whereby the shaft wipers are 55 rotated onto the contacts of the desired line. The circuit through the rotary magnet extends from ground G⁹ through springs 99 and 100, springs 101 and 102, relay 53, rotary magnet 40, and the side switch wiper 41 (in 60 second position) to battery B. The relay 65

53 operates in response to this digit in the same manner as for the previous digit, to cause the private magnet 45 to advance the side switch to third position. By the engagement of side switch wipers 42 and 43 with their third position contact points, the line connection is completed with the called line. Upon the engagement of side switch wiper 44 with its third position contact point, a circuit is completed through the cut-off winding 107 of the line switch C', which upon energizing, disconnects the line relay from the called line. The connection of ground G¹¹ with the connector private bank contact associated with the called line, 70 prevents the called line from being seized by some other connector switch. By the engagement of side switch wiper 41 with its third position contact point, the circuit of the ringer relay 48 is closed. This circuit extends from ground G¹² through interrupter 108, ringer relay 48, springs 109, and the side switch wiper 41 (in third position) to battery B. The ringer relay is energized intermittently due to the interrupter 108, 75 and operates to disconnect the calling line from the called line, and to bridge the ringing current generator R across the called line to signal the called subscriber. Upon the response of the called subscriber, his line is provided with talking current through the windings of the back bridge relay 47, which relay, upon energizing, closes the circuit through the ringer cut-off relay 110. The said circuit extends from ground G¹¹ through side switch wiper 44 (in third 80 position) springs 111 and the relay 110 to battery B. The relay 110, upon energizing opens the circuit of the ringer relay 48 at the springs 109, and closes a locking circuit for itself, through the springs 112 independent of springs 111. This circuit extends from ground G¹¹ through side switch wiper 44 (in third position), contacts of springs 112, and relay 110 to battery B. Furthermore, the back bridge relay 47, upon energizing, operates to reverse the direction of the flow of current in the trunk, with a result hereinafter described. 85

When the operator has completed dialing 115 the called number, she restores the key K' to normal thereby again connecting the answering and calling ends of the cord circuit and at the same time opening the bridge consisting of the calling device 78. It will be observed that the polarized relay 35 is now bridged across the trunk in place of the bridge consisting of the calling device 78. The polarized relay 35 will become energized in a direction to close a circuit through lamp 34; the glowing of lamp 34 120 will inform the operator that the called subscriber has not answered. Upon the called subscriber removing his receiver, the back bridge relay operates to reverse the 125 130

flow of current in the trunk as previously explained, whereupon the polarized relay 35 is energized in a direction to open the circuit of the lamp 34, thereby notifying 5 the operator that the called subscriber has answered. It may be mentioned here that the relay 35, being slow acting, has remained in an energized position throughout the transmission of the impulses.

10 Upon the completion of the conversation, the hanging up of the receiver at the calling substation opens the circuit of relay 77, which, upon deenergizing, closes the circuit of lamp 33. The hanging up of the receiver 15 at the called substation opens the circuit of the back bridge relay 47, which, upon deenergizing, again reverses the current in the trunk to such a direction that the polarized relay 35 again closes the circuit of the 20 lamp 34. The operator, upon seeing both the lamps 33 and 34 glowing, knows that a disconnect is required and thereupon removes the plugs P and P' from their respective jacks. The removal of plug P 25 opens the circuit of the cut-off relay 29, which, upon deenergizing, opens the circuit of the holding winding 16. Upon the deenergization of the holding winding 16, the plunger arm 13 is released and the line 30 switch C thereupon returns to normal. The removal of the plug P' opens the circuit of the line relay 46 of the connector H. The deenergization of relay 46 opens the circuit of relay 52, which in turn, upon deenergizing, closes a circuit extending from 35 ground G⁹ through springs 99 and 100, springs 101 and 113, off normal springs 50, and the release magnet 49 to battery B. The release magnet, upon energizing, operates to restore the side switch wipers to their 40 first position and to remove the retaining double-dog from the shaft, thus allowing the shaft to drop to its normal position, and its own circuit is opened at the springs 45 50 when said shaft reaches its lowest position. In addition, the deenergization of relay 52 opens the circuit of the holding winding of the line switch C², whereupon line switch C² releases in the same manner as explained in connection with line switch C.

It having been explained how one subscriber obtains connection and the same is released, it will now be explained how a connection is prevented from being made with 55 a busy line. If the called number is busy there will be a guarding ground potential upon the connector private bank contacts, associated with that line, just as explained in connection with the line switch C. When, 60 therefore, the slow acting relay 53 deenergizes at the end of the last series of impulses, a circuit is completed for the busy test relay 114 and the private magnet 45 over the following path: ground at the private bank 65 contact, private wiper 37, side switch wiper

44 (in second position) springs 115 and 116, relay 114, springs 117 and 104, and the private magnet 45 to battery B. The relay 114, upon energizing, forms a locking circuit for itself extending from ground G¹³ through 70 off normal springs 51, springs 118 and 116; relay 114, springs 117 and 104, and the private magnet 45 to battery B. In addition, the relay 114, upon energizing, separates the springs 119, thereby opening the circuit of 75 the line relay 46 and the relay 85, of cord circuit F, in series therewith. As a result of the deenergization of the line relay 46 the circuit of relay 52 is broken, whereupon the release of the connector H and the line 80 switch C² takes place as previously explained. It should be mentioned in this connection that while relays 85 and 52 are both sufficiently slow acting to retain their armature during impulses, the latter relay 85 should be somewhat the slower of the two. Furthermore, since the circuit of relay 85 is interrupted slightly before that of relay 52 is interrupted, it follows that soon after the opening of the circuit of the line relay 90 46, and before the deenergization of relay 52, the slow acting relay 85 deenergizes and closes a circuit extending from ground G¹⁴, through springs 96, sleeve of jack J', sleeve of plug P', relay 97, and the springs 98 to 95 battery B. The relay 97, upon energizing, completes a circuit extending from ground G¹⁵ through springs 120 and the relay 121 to battery B. The relay 121, upon energizing, forms a locking circuit for itself 100 from ground G⁴ through plug seat springs 71, springs 122, and the relay 121 to battery B, and at the same time, by separating springs 84, opens the original energizing circuit for the line winding of line switch 105 C² so that the automatic switches upon their complete restoration to normal will not again be operated. After the calling device has been operated the operator restores key K' to its normal position thereby completing 110 the circuit over the heavy conductors to the calling line and disconnecting the calling device. The polarized relay 35 being at this time in open circuit, its armature will be held in the direction to keep the circuit of lamp 34 open. In addition a circuit is closed from ground G¹⁶ through interrupter 123, springs 124, and the lamp 34, to battery B. The lamp will be flashed intermittently, due to the interrupter 123 and this 120 informs the operator that the line called is busy.

Furthermore, and at the same time, a circuit is closed from the secondary winding of busy machine Q, springs 125, condenser 32, 125 over heavy conductors to and through substation A, relay 74 to ground G⁶ and return to busy machine Q. The calling subscriber upon hearing the busy tone will restore his receiver to the switch hook, thus giving the 130

operator the disconnect signal as previously explained. The operator, upon observing the flashing of the lamp 34, is thereby informed that the called line is busy and, provided the calling subscriber has already hung up his receiver, she may remove the plugs from the jacks. In case, however, the calling subscriber has not hung up his receiver or does not understand the significance of the signal he receives, the operator may throw her keys K and K' and is then able to inform the subscriber of the inaccessibility of the desired line.

It will be seen that during the entire busy signaling operation above described the connector H is entirely free and is accessible to other line switches such as C². It may, in fact, be seized and used for establishing a new connection immediately after its restoration to normal.

While we have described in the foregoing a certain specific embodiment of our invention, we do not wish to be held strictly to the exact form shown herein, for various adaptations will no doubt suggest themselves to persons skilled in the art. We desire, therefore, to include and have protected by Letters Patent all forms and modifications of our invention which may come within the scope of the appended claims.

What we claim is:

1. In a trunking system, a line, a plurality of automatic switches having access to said line, means for operating any one of said switches to find the line, means for releasing whichever switch is so operated, an equipment including a pair of signaling circuits, a signal for each of said circuits, means associated with said equipment for applying signaling current to said circuits, means for applying said equipment to any one of said switches whereby, when the line is found and the switch releases, said means associated with said equipment is controlled to simultaneously operate said signals.

2. In a trunking system, a line, a plurality of automatic switches having access to said line, means for operating any one of said switches to find the line, means for releasing whichever switch is so operated, an equipment including a pair of signaling circuits, a signal individual to one of said circuits and a plurality of signals associated with the other circuit, means for connecting said other circuit with any one of its associated signals, means associated with said equipment for applying signaling current to said circuits, means for applying said equipment to any one of said switches whereby, when the line is found and the switch releases, said means associated with said equipment is controlled to simultaneously operate said signals.

3. In a trunking system, a line, a plurality of automatic switches having access to said

line, means for operating any one of said switches to find the line, means for releasing whichever switch is so operated, an equipment including a pair of signaling circuits, a signal for each of said circuits, means associated with said equipment for applying signaling current to said circuits, semi-automatic means for applying said equipment to any one of said switches whereby, when the line is found and the switch releases, said means associated with said equipment is controlled to simultaneously operate said signals.

4. In a trunking system, a line, a plurality of automatic switches having access to said line, means for operating any one of said switches to find the line, means for releasing whichever switch is so operated, an equipment including a pair of signaling circuits, a signal for each of said circuits, means associated with said equipment for applying signaling current to said circuits, semi-automatic means including a second automatic switch for applying said equipment to any one of said switches whereby, when the line is found and the switch releases, said means associated with said equipment is controlled to simultaneously operate said signals.

5. In a trunking system, a line, a plurality of automatic switches having access to said line, means for operating any one of said switches to find the line, means for releasing whichever switch is so operated, an equipment including a pair of signaling circuits, a signal individual to one of said circuits and a plurality of signals associated with the other circuit, means for connecting said other circuit with any one of its associated signals, means associated with said equipment for applying signaling current to said circuits, means for applying said equipment to any one of said switches whereby, when the line is found and the switch releases, said means associated with said equipment is controlled to simultaneously operate said signals.

6. In a trunking system, a line, a plurality of automatic switches having access to said line, means for operating any one of said switches to find the line, means for releasing whichever switch is so operated, an equipment including a pair of signaling circuits, a signal for each of said circuits, means associated with said equipment for applying signaling current to said circuits, semi-automatic means comprising a second automatic switch for applying said equipment to any one of said switches whereby, when the line is found and the switch releases, said means associated with said equipment is controlled to simultaneously operate said signals, and said second switch is released.

7. In a trunking system, a line, a plurality

- of automatic switches having access to said line, means for operating any one of said switches to find the line, means for releasing whichever switch is so operated, an equipment including a pair of signaling circuits, a signal for each of said circuits, means associated with said equipment for applying signaling current to said circuits, means for applying said equipment to any one of said switches whereby, when the line is found and the switch releases, said means associated with said equipment is controlled to simultaneously operate said signals, and an interrupter for one of said signaling circuits to render the associated signal intermittent. 8. In a telephone system, a plurality of lines, a plurality of cord circuits, an automatic switch having access to said lines, means whereby a connection may be established between a calling and a called line through the medium of any one of said cord circuits and said switch, a signal associated with each of said cord circuits, means whereby upon the attempt to complete a connection with a busy line said switch is released, and means included in the selected cord circuit and made effective upon the release of said switch, whereby said switch is rendered accessible to the remainder of said cord circuits, and whereby the signal associated with the selected cord circuit is operated. 9. In a telephone system, a plurality of lines, a plurality of cord circuits, a plurality of automatic switches having access to said lines, means whereby a connection may be established between a calling and a called line through the medium of any one of said cord circuits and a selected one of said switches, a signal associated with each of said cord circuits, means whereby upon the completion of a connection to a busy line the selected switch is released and means included in the selected cord circuit and made effective upon the release of said switch, whereby said switch is rendered accessible to the remainder of said cord circuits, and whereby the associated signal of the selected cord circuit is operated. 10. In a telephone system, a plurality of lines, a cord circuit, an automatic switch having access to said lines, means whereby a connection may be established between a calling and a called line through the medium of said cord circuit and said switch, a signal associated with said cord circuit, a circuit for said signal, means whereby upon the completion of a connection to a busy line said switch is released, means included in said cord circuit and rendered effective upon the release of said switch for closing the circuit of said signal, and an interrupter in said circuit for making the operation of said signal intermittent in character. 11. In a telephone system, a plurality of lines, a plurality of cord circuits, an automatic switch having access to said lines, means whereby a connection may be established between a calling and a called line through the medium of any one of said cord circuits and said switch, a signal associated with each of said cord circuits, means whereby upon the completion of a connection to a busy line said switch is released, means included in the selected cord circuit and made effective upon the release of said switch, whereby said switch is rendered accessible to the remainder of said cord circuits, and whereby the associated signal of the selected cord circuit is operated. 12. In a telephone system, a plurality of lines, a cord circuit, a plurality of automatic switches having access to said lines, means whereby a connection may be established between a calling and a called line through the medium of said cord circuit and a selected one of said switches, a signal associated with said cord circuit, a circuit for said signal, means whereby upon the completion of a connection to a busy line the selected switch is released, means included in said cord circuit and rendered effective upon the release of said switch for closing the circuit of said signal, and an interrupter in said circuit for making the operation of said signal intermittent in character. 13. In a telephone system, a plurality of lines, a plurality of cord circuits, a plurality of automatic switches having access to said lines, means whereby a connection may be established between a calling and a called line through the medium of any one of said cord circuits and a selected one of said switches, a signal associated with each of said cord circuits, means whereby upon the completion of a connection to a busy line the selected switch is released, means included in the selected cord circuit and made effective upon the release of said switch, whereby said switch is rendered accessible to the remainder of said cord circuits and whereby the associated signal of the selected cord circuit is operated, and associated means for making the operation of said signal intermittent in character. 14. In a telephone system, a plurality of lines, a cord circuit, an automatic switch having access to said lines, means whereby a connection may be established between a calling and a called line through the medium of said cord circuit and said switch, a signal associated with said cord circuit, a circuit for said signal, means whereby upon the completion of a connection to a busy line said switch is released, means included in said cord circuit and made effective upon the release of said switch for closing the circuit of said signal, and associated means for transmitting a distinctive tone to the

calling line, said last means also controlled by the means included in said cord circuit.

15. In a telephone system, a plurality of lines, a plurality of cord circuits, an automatic switch having access to said lines, means whereby a connection may be established between a calling and a called line through the medium of any one of said cord circuits and said switch, a signal associated with each of said cord circuits, means whereby upon the completion of a connection to a busy line said switch is released, means included in the selected cord circuit and made effective upon the release of said switch, whereby said switch is rendered accessible to the remainder of said cord circuits and whereby the signal associated with the selected cord circuit is operated, and associated means for transmitting a distinctive tone to the calling line.

16. In a telephone system, a plurality of lines, a cord circuit, a plurality of automatic switches having access to said lines, means whereby a connection may be established between a calling and a called line through the medium of said cord circuit and a selected one of said switches, a signal associated with said cord circuit, a circuit for said signal, means whereby upon the completion of a connection to a busy line the selected switch is released, means included in said cord circuit and made effective upon the release of said switch for closing the circuit of said signal, and associated means for transmitting a distinctive tone to the calling line, said last means also controlled by the means included in said cord circuit.

17. In a telephone system, a plurality of lines, a plurality of cord circuits, a plurality of automatic switches having access to said lines, means whereby a connection may be established between a calling and a called line through the medium of any one of said cord circuits and a selected one of said switches, a signal associated with each of said cord circuits, means whereby upon the completion of a connection to a busy line the selected switch is released, means included in the selected cord circuit and made effective upon the release of said switch, whereby said switch is rendered accessible to the remainder of said cord circuits, and whereby the associated signal of the selected cord circuit is operated, and associated means for transmitting a distinctive tone to the calling line.

18. In a trunking system, an automatic switch, an operating circuit therefor, said operating circuit having a terminal connection, a plurality of extensions having access in common to said connection, a line accessible to said switch, a busy test circuit for said line, means controlled over said test circuit for controlling said operating

circuit, a relay in each of said extensions, 65 and a controlling relay for each of said extensions under the control of said first relay.

19. In a trunking system, an automatic switch, an operating circuit therefor, said operating circuit having a terminal connection, a plurality of extensions having access in common to said connection, a line accessible to said switch, a busy test circuit for said line, means controlled over said test 70 circuit for controlling said operating circuit, a relay in each of said extensions, a controlling relay for each of said extensions under the control of said first relay, a signal and a circuit therefor controlled by said 75 controlling relay.

20. In a trunking system, an automatic switch, an operating circuit therefor, said operating circuit having a terminal connection, a plurality of extensions having access 80 in common to said connection, a line accessible to said switch, a busy test circuit for said line, means controlled over said test circuit for controlling said operating circuit, a relay in each of said extensions, a 85 controlling relay for each of said extensions under the control of said first relay, a signal and a circuit therefor controlled by said 90 controlling relay, and means for intermittently interrupting the circuit of said signal. 95

21. In a trunking system, an automatic switch, an operating circuit therefor, said operating circuit having a terminal connection, a plurality of extensions having access in common to said branch, a line accessible 100 to said switch, a busy test circuit for said line, means controlled over said test circuit for controlling said operating circuit, a relay in each of said extensions, a controlling relay for each of said extensions under the control of said first relay, and a plurality 105 of signaling circuits controlled by said controlling relay.

22. In a trunking system, an automatic switch, an operating circuit therefor, said 110 operating circuit having a terminal connection, a plurality of extensions having access in common to said connection, a line accessible to said switch, a busy test circuit for said line, means controlled over said test 115 circuit for controlling said operating circuit, a relay in each of said extensions, a controlling relay for each of said extensions under the control of said first relay, a plurality 120 of signaling circuits controlled by said controlling relay, and means for intermittently interrupting one of said signaling circuits.

23. In a telephone system, a line, a plurality of trunk lines, an automatic switch 125 having access to said line and normally accessible from each of said trunk lines, means including one of a plurality of cord cir-

cuits whereby an operating circuit for said switch may be established over one of said trunk lines, a relay in said cord circuit for controlling said operating circuit, and means effective when said switch is operated to connect with said line in its busy condition for restoring said switch to its normal condition and for initially operating said relay.

24. In a telephone system, a line, a plurality of trunk lines, an automatic switch having access to said line and normally accessible from each of said trunk lines, means including one of a plurality of cord circuits whereby an operating circuit for said switch may be established over one of said trunk lines, a relay in said cord circuit for controlling said operating circuit, means effective when said switch is operated to connect with said line in its busy condition for restoring said switch to its normal condition and for initially operating said relay, and means for maintaining said relay in operated position whereby a new operating circuit for said switch may be established by 25 means of another of said cord circuits and another of said trunk lines.

25. In a telephone system, a line, a plurality of trunk lines, an automatic switch having access to said line and normally accessible from each of said trunk lines, means including one of a plurality of cord circuits whereby an operating circuit for said switch may be established over one of said trunk lines, a relay in said cord circuit for controlling said operating circuit, means effective when said switch is operated to connect with said line in its busy condition for restoring said switch to its normal condition and for initially operating said relay, and a 40 signal controlled by said relay.

26. In a telephone system, a line, a plurality of trunk lines, an automatic switch having access to said line and normally accessible from each of said trunk lines, means including one of a plurality of cord circuits whereby an operating circuit for said switch may be established over one of said trunk lines, a relay in said cord circuit for controlling said operating circuit, means effective when said switch is operated to connect with said line in its busy condition for restoring said switch to its normal condition and for initially operating said relay, means for maintaining said relay in operated position whereby a new operating circuit for said switch may be established by means of another of said cord circuits and another of said trunk lines, and a signal controlled by said relay.

27. In a telephone system, a calling and a called line, a cord circuit and an automatic switch for connecting the two lines, a supervisory signal in said cord circuit under the control of the called line after connection

therewith has been established, means effective when said called line is busy for preventing connection thereto and for releasing said switch, auxiliary controlling means in said cord circuit for said signal initially operated through the medium of said first means, means for securing the continued operation of said auxiliary controlling means until the disconnection of said calling line independent of said switch.

28. In a telephone system, a calling and a called line, a cord circuit and an automatic switch for connecting the two lines, a supervisory signal in said cord circuit under the control of the called line after connection therewith has been established, means effective when said called line is busy for preventing connection thereto and for releasing said switch, auxiliary controlling means in said cord circuit for said signal initially operated through the medium of said first means, and means for indicating during the operation of the signal whether it is controlled by the called line or by its auxiliary controlling means.

29. In a telephone system, a calling and a called line, a cord circuit and an automatic switch for connecting the two lines, a supervisory signal in said cord circuit under the control of the called line after connection therewith has been established, means effective when said called line is busy for preventing connection thereto and for releasing said switch, auxiliary controlling means in said cord circuit for said signal initially operated through the medium of said first means, means for securing the continued operation of said auxiliary controlling means independent of said switch, and means for indicating during the operation of the signal whether it is controlled by the called line or by its auxiliary controlling means.

30. In a telephone system, a calling and a called line, a cord circuit and an automatic switch for connecting the two lines, a supervisory signal in said cord circuit under the control of the called line after connection therewith has been established, means effective when said called line is busy for preventing connection thereto and for releasing said switch, auxiliary controlling means in said cord circuit for said signal initially operated through the medium of said first means, means for securing the continued operation of said auxiliary controlling means until the disconnection of said calling line independent of said switch, and means for indicating during the operation of the signal whether it is controlled by the called line or by its auxiliary controlling means.

31. In a telephone system, a calling and a called line, a cord circuit and an automatic switch for connecting the two lines, a super-

visory signal in said cord circuit under the control of the called line after connection therewith has been established, means effective when said called line is busy for preventing connection thereto and for releasing said switch, auxiliary controlling means in said cord circuit for said signal initially operated through the medium of said first means, means for indicating during the 10 operation of the signal whether it is controlled by the called line or by its auxiliary controlling means, and means under the control of said auxiliary controlling means for transmitting a distinctive tone over the 15 calling line.

32. In a telephone system, a calling and a called line, a cord circuit and an automatic switch for connecting the two lines, a supervisory signal in said cord circuit under the 20 control of the called line after connection therewith has been established, means effective when said called line is busy for preventing connection thereto and for releasing said switch, auxiliary controlling means in said cord circuit for said signal initially operated through the medium of said first means, means for securing the continued 25 operation of said auxiliary controlling means independent of said switch, means for indicating during the operation of the signal whether it is controlled by the called line or by its auxiliary controlling means, and means under the control of said auxiliary 30 controlling means for transmitting a distinctive tone over the calling line.

33. In a telephone system, a calling and a called line, a cord circuit and an automatic switch for connecting the two lines, a supervisory signal in said cord circuit under the 40 control of the called line after connection therewith has been established, means effective when said called line is busy for preventing connection thereto and for releasing said switch, auxiliary controlling means in said cord circuit for said signal initially operated through the medium of said first means, means for securing the continued 45 operation of said auxiliary controlling means until the disconnection of said calling line independent of said switch, means for indicating during the operation of the signal whether it is controlled by the called line or by its auxiliary controlling means, and means under the control of said auxiliary 50 controlling means for transmitting a distinctive tone over the calling line.

34. In a telephone system, a line, a plurality of trunk lines, an automatic switch having access to said line and accessible 60 from each of said trunk lines, means including a cord circuit whereby an operating circuit for said switch may be established over one of said trunk lines, a test circuit individual to said switch, means for placing

ing a potential on said test circuit when said operating circuit is established to make the switch busy, a relay in said cord circuit for interrupting said operating circuit, means in said switch effective upon the operation of said switch to connect with said line in its busy condition for interrupting said operating circuit to release said switch and remove the potential from said test circuit, and a second relay in said cord circuit responsive to interruption of said operating 75 circuit for initially controlling said first relay.

35. In a telephone system, a line, a plurality of trunk lines, an automatic switch having access to said line and accessible 80 from each of said trunk lines, means including a cord circuit whereby an operating circuit for said switch may be established over one of said trunk lines, a test circuit individual to said switch, means for placing a 85 potential on said test circuit when said operating circuit is established to make the switch busy, a relay in said cord circuit for interrupting said operating circuit, means in said switch effective upon the operation 90 of said switch to connect with said line in its busy condition for interrupting said operating circuit to release said switch and remove the potential from said test contact, a second relay in said cord circuit responsive 95 to interruption of said operating-circuit for initially controlling said first relay, and means for maintaining said first relay in operated position independent of said operating circuit and of said switch. 100

36. In a telephone system, calling and called lines, a plurality of automatic switches having access to called lines, manual equipment for controlling one of said switches to find said called line, a signal for said calling line and a signal in said equipment, means for releasing said switch when the called line is busy, and a relay in said equipment operated when the switch is released to operate said signals. 105

37. In a telephone system, calling and called lines, an automatic switch, manual equipment for controlling said switch to seize a called line, testing equipment for said switch, a signal for said calling line 115 and a signal for said manual equipment, a relay in said manual equipment for controlling the operation of both signals, said testing equipment being operated when the called line is busy to release said switch and 120 operate said relay.

38. In a telephone system, an automatic switch, an operating circuit therefor, a line accessible to said switch, a busy test circuit for said line, a relay in said test circuit, a 125 relay in said operating circuit individual to said switch, another relay in said operating circuit common to a number of said

switches, said first relay controlled over said test circuit to control said operating circuit, whereby said second and third relays are operated, said second relay controlling the 5 release of said switch and said third relay controlling said operating circuit.

Signed by me at city of Chicago, Cook

county, Illinois, this 15th day of February, 1916.

GEORGE A. YANOCHOWSKI. 10

Signed by me at city of St. Paul, Ramsey county, Minnesota, this 12th day of February, 1916.

HARRY E. HERSHY.
